F. E. ROBERTSON,
SUCTION CLEANING APPARATUS,
APPLICATION FILED OCT. 31, 1917.

Patented Dec. 5, 1922.

Inventor,
Frank E. Robertson,

By J. C. Duncan
Attorney.

UNITED STATES PATENT OFFICE.

FRANK E. ROBERTSON, OF CLEVELAND, OHIO, ASSIGNOR TO THE P. A. GEIER COMPANY,
OF CLEVELAND, OHIO, A CORPORATION OF OHIO.

SUCTION CLEANING APPARATUS.

Application filed October 31, 1917. Serial No. 199,502.

To all whom it may concern:

Be it known that FRANK E. ROBERTSON, a citizen of the United States, residing at Cleveland, in the county of Cuyahoga and 5 State of Ohio, has invented certain new and useful Improvements in Suction Cleaning Apparatus, of which the following is a specification.

My invention relates to improvements in 10 dust receptacles for suction cleaning apparatus, and has for its object the provision of a support and mounting for the fabric dust-container or bag of such devices, which avoids the necessity for any valved retaining member for the contents thereof, and permits the ready emptying of the bag, yet holds it securely in position during use.

The receptacle in part, preferably comprises an integral portion of the fan-casing, 20 in the portable, electrically-driven type of apparatus which I have shown in connection with my improvement. Said fan-casing affords a frame on which the dust-bag is removably attached, and a barrier positioned before the mouth of the bag or the lower portion thereof, for retaining the contents of the bag therein. Attaching means, such as wedging interiorly placed hooks and lugs, or screw or spring-clamping mechanism, alternatively serve to support thereon, the frame forming the mouth of the bag, removably in place upon the fan-casing.

Further features of construction and the attendant advantages thereof will be more 35 readily understood by making reference to the accompanying description and drawings, wherein:

Fig. 1 is a view in side elevation of a suction cleaner equipped with my improvements;

Fig. 2 is an enlarged fragmentary view thereof, partially broken away;

Fig. 3 is a rear view of the fan-casing with the integral barrier and wedging 45 hooks;

Fig. 4 is a fragmentary view of an attaching means, and

Fig. 5 illustrates, in section, a co-acting spring-clip.

50 Fig. 6 is a fragmentary section showing the dust collected in the upturned bag before the barrier.

Throughout the several figures of the drawings I have employed the same character of reference to indicate similar parts.

The general features of a well known type of electrically actuated suction cleaner are shown in Fig. 1, of which the suction-nozzle *a*, the dust-bag *b* and fan-casing *c* will immediately be recognized. As shown in Fig. 60 3 upon a much larger scale, the fan-casing comprises the fan-chamber *c'* with its exhaust-opening *c''* and a lateral extension *d* for the discharge of the fan. Upon this extension, integral with the casing, is removably mounted the fabric dust-bag or receptacle *b*. The lower portion of said extension is closed by a wall or barrier *d'*, mounting the paired wedging-hooks *d''*, as best shown at the broken-away portion, Fig. 2. 70

Co-operating with these hooks *d''* are the corresponding lugs *e''* interiorly positioned within the approximately oval frame *e*, reinforcing and shaping the mouth of bag *b*. This frame *e* conforms in shape to the rear 75 face of extension *d*, against which the frame forming the mouth of the bag is adapted to be brought closely in flush contact, by means of the wedging hooks and co-acting lugs. The oval conformation of the bag mouth 80 best lends itself to the type of fan-casing shown, as equipped with a free upper discharge opening *c''* and a bottom wall or barrier *d'*. Moreover, it is positioned compactly, close to the motor casing indicated 85 in dotted lines, Fig. 1, which is bolted to the seat *c'''* adjacent to the rear of extension *d* and its seat for the dust receptacle.

When the receptacle is in place, the mouth of the bag is brought accurately and closely 90 into register with the oval portion of the fan-casing. In this position the integral wall *d'* forms a complete barrier against the return passage of dust and refuse from said bag, collecting as it must, in the lower 95 portion of said bag and against the barrier *d'*. Thus no valved construction is necessary for the retention of the dirt and no external fastening means are required for the bag.

In Figs. 3 and 4 are shown means, co-operating with the hooks *d''*, for locking the frame *e* positively against displacement, if desired. These means comprise a thumb-nut *e'* provided for engaging and securing the 105 slotted upper corner *e''* of the frame *e* rigidly in place. In addition, these same means may be employed in connection with a spring clip *f* taking against the diagonally positioned corner of the frame, where- 110

by an alternative blower attachment (not shown) may be attached to the casing instead of the dust receptacle.

Having now set forth with some detail, the 5 preferred embodiment of my invention, I claim as new and desire to secure by Letters Patent, together with such modifications as may be made therein by mere skill, the following:—

- 10 1. The combination with a suction-cleaner having a fan-casing equipped with a lateral extension affording an elongated exterior seat including a free exhaust-opening and a barrier member, of a dust-receptacle re- 15 movably positioned before said extension, and fitting said exterior seat on the fan casing, and means for removably securing said dust-receptacle to the fan-casing, sub-stantially as set forth.
- 20 2. The combination with a suction-cleaner having a motor casing and a fan-casing equipped with an extension affording an elongated exterior seat including a free exhaust-opening and a barrier member 25 positioned beneath said opening, of a dust receptacle having a conforming elongated mouth positioned adjacent to the motor casing to register with said opening and barrier and extending below the upper edge 30 of the latter, and means for removably se- curing the dust-receptacle upon said exten- sion, substantially as set forth.
- 35 3. The combination with a fan-casing of a portable suction-cleaner, of a fabric dust receptacle, a frame defining the open mouth of said receptacle and adapted to fit upon said fan-casing, wedging means exterior of said casing over which the frame normally is exteriorly positioned to enclose said means, 40 whereby the open mouth of said receptacle is removably sealed against the exterior of said fan-casing, and additional locking means interposed between the frame and casing substantially as set forth.
- 45 4. The combination with the fan-casing of a suction-cleaner, of a dust receptacle, a frame defining the open mouth of said re- ceptacle, and rearward wedging hooks and 50 coacting lugs respectively provided upon the fan-casing and the frame, whereby the latter

may be removably secured by said lugs in close engagement with the exterior of the fan-casing, substantially as set forth.

5. The combination with the fan-casing of a suction-cleaner, of a dust receptacle, wedg- 55 ing means interposed between the casing and receptacle for removably engaging the mouth of said receptacle with its seat upon the fan-casing, and positive locking means upon the casing for retaining said dust re- 60 ceptacle temporarily in place thereon, sub-stantially as set forth.

6. The combination with the fan-casing of a suction cleaner having an exterior seat for its dust-receptacle, an exhaust opening 65 and a dust-retaining member within the boundaries of said seat, wedging hooks posi- tioned upon the casing also within the bound-aries of said seat, a frame defining the opening and its dust-receptacle normally 70 supported in inclined position before said dust-retaining member, and interiorly posi- tioned means for engaging said wedging hooks, substantially as set forth.

7. In a portable suction cleaner, the com- 75 bination with a fan-casing having a sub-stantially vertical exterior seat for the dust receptacle, an exhaust opening and a sub-adjacent dust barrier within the boundaries of said seat, of upwardly inclined wedging 80 hooks upon the casing, a dust receptacle nor-mally supported by said hooks, and means associated therewith for engaging the mouth of said receptacle in close wedging engage- 85 ment with the seat, substantially as set forth.

8. In a portable suction cleaner, the com- bination with a fan casing having a substan-tially vertical exterior seat, of upwardly in- 90 clined wedging hooks laterally provided within its boundaries, a dust receptacle nor-mally supported with its mouth engaging said seat, and means associated therewith for wedgingly engaging the hooks, substantially as set forth.

In testimony whereof I do now affix my 95 signature in the presence of two witnesses.

FRANK E. ROBERTSON.
